(57) **CLAIM**

The ornamental design for a ceiling fan, as shown and described.

DESCRIPTION

FIG. 1 is a top perspective view of a ceiling fan showing my new design;
FIG. 2 is a bottom perspective view of the ceiling fan of FIG. 1;

FIG. 3 is a top view of the ceiling fan of FIG. 1;

FIG. 4 is a bottom view of the ceiling fan of FIG. 1; and,

FIG. 5 is a front side view of the ceiling fan of FIG. 1 with rear, left, and right side views being mirror images thereof. Portions of the ceiling fan shown in broken lines form no part of the claimed design.

1 Claim, 5 Drawing Sheets(56)
